UNITED STATES PATENT OFFICE.

WILLIAM HENRY LEAMAN, JR., OF MERIDEN, CONNECTICUT.

HOLDER FOR FLY-PAPER.

1,239,703.

Specification of Letters Patent. Patented Sept. 11, 1917.

Application filed December 15, 1916. Serial No. 137,154.

To all whom it may concern:

Be it known that I, WILLIAM H. LEAMAN, Jr., a citizen of the United States, residing at Meriden, in the county of New Haven, 5 State of Connecticut, have invented a new and useful Holder for Fly-Paper; and I do hereby declare the following to be a full, clear, and exact description of the invention, such as will enable others skilled in the 10 art to which it appertains to make and use the same.

This invention relates to an improved holder for flypaper, whereby flies may be caught on the wall, ceiling or upon any 15 other surface.

One of the objects of the invention is to provide a flanged body having improved means for detachably holding a sheet of flypaper, whereby, when the flanged body is 20 placed over a fly on the wall or ceiling, the fly will endeavor to escape in the direction of the flypaper and become caught, in other words, entrapped, owing to the flanges of the body preventing the escape of the fly in 25 different directions.

A further object of the invention is to provide improved means for attaching a stick, rod or pole to the flanged body detachably.

30 A further object of the invention is to provide means whereby the body may be moved to different angles.

In practical fields, the details of construction may necessitate alterations falling 35 within the scope of what is claimed.

The invention comprises further features, and combination of parts, as hereinafter set forth, shown in the drawings, and claimed.

In the drawings:—

40 Figure 1 is a view in perspective of the improved combined flypaper holder and catcher, constructed in accordance with the invention.

Fig. 2 is a sectional view on line 2—2 of 45 Fig. 1.

Fig. 3 is a bottom plan view of the holder or flycatcher.

Fig. 4 illustrates views of the means for 50 pivotally and detachably connecting a pole to the bottom of the holder.

Referring more especially to the drawings, 1 designates a body comprising the bottom 2 and the side flanges 3 and 4. This body is constructed from a single piece of 55 sheet metal, which is stamped or constructed to form the bottom and side flanges.

These flanges at their upper edge portions are provided with rolls 5, to receive the stiffening or strengthening wire 6. However, the rolls at corners of the body are cut 60 away, thereby leaving the wire uncovered. One of the sides 3 or flanges is provided with inwardly extending ears or lugs 7, which are struck up from portions 8 of the roll of the respective flange 3. These ears 65 or lugs project through the openings 9 of one of the flanges 3, and are just high enough from the bottom of the body to permit one edge portion of a piece of fly paper to engage thereunder to assist in holding the 70 fly paper in place. The other flange 3 has riveted thereto by means of the rivets 10 on the exterior of the flange, a leaf spring 11, which has a laterally extending lug 12, to extend through an opening 13 of said flange 75 3, and is just high enough from the bottom of the body to permit the opposite edge portion of the sheet of fly paper to engage under the same. It is to be noted that by pulling the leaf spring outwardly, the lug 12 80 may be pulled through its opening 13, to permit the insertion and removal of the fly paper.

Secured upon the bottom or under face of the body by soldering or the like is a 85 pair of wire members 14, which extend from near the center of the underface of the body toward the corners thereof, and terminate in coiled eyes 15, forming legs whereby the body may be supported upon a table or the 90 like.

Secured to the underface of the body by means of rivets or the like 16 is a plate 17, which is provided with ears 18 struck up from the plate. A staff or pole 19 is provided, whereby the body may be connected thereto. One end of this pole or staff has a reduced part 20, which is secured in a cap sleeve 21 by means of a transverse pin 22. This cap sleeve is exteriorly threaded, in 100 order to be threaded into coupling sleeve 23, which is provided with a V-shaped lug 24, which is flat, and is in turn pivoted between the ears 18 on the pin 25. By this construction of joint between the flanged body and the pole or staff, the staff may be easily detached, and the flanged body may be disposed in different pivotal positions, so that flies may be caught on the side walls or the ceiling of a room, or on any other surface of 105 a different angle. In other words, the flanged body may be disposed substantially

parallel with the surface with which it is to be engaged, then the body may be placed over the flies to be caught, the fly in its endeavor to escape will strike on the sticky 5 surface of the fly paper.

The invention having been set forth, what is claimed as new and useful is:—

A flypaper holder, comprising a body having flanges upon four of its edge portions having their upper portions provided with rolls, parts of the roll of one of said flanges having extension tongues, the flanges adjacent said tongues having openings, through which tongues are bent forming 15 lugs under which one edge of a piece of flypaper engages, the flange opposite the flange having the first openings having an open-

ing, and a leaf spring secured to the flange having the last named opening and provided with a lug protruding through said last named opening, and under which the opposite edge portion of said sheet of flypaper engages, and a pair of wires secured to the bottom of the body and extending toward the corners thereof and terminating in 20 coiled eyes forming feet, to support the body.

In testimony whereof I have signed my name to this specification in the presence of two subscribing witnesses.

WILLIAM HENRY LEAMAN, JR.
